TENSION BAND

Leo J. Martini, South Gate, Calif., assignor to Master
Fence Fittings, Inc., La Habra, Calif.

Filed June 29, 1973, Ser. No. 375,117

Term of patent 14 years

Int. Cl. D8—08

U.S. Cl. D8—259

FIG. 1 is a perspective view of a tension band showing the front, top and right side in the open position of my new design;

FIG. 2 is a perspective view showing the rear, bottom and left side of the tension band in the open position thereof;

FIG. 3 is a perspective view showing the front, top and right side of the tension band in closed position thereof;

FIG. 4 is a perspective view showing the rear, bottom and left side of the tension band in closed position thereof.

I claim:

The ornamental design for a tension band, as shown.
